UNITED STATES PATENT OFFICE.

FREDERICK W. SAWORSKI, OF BOSTON, MASSACHUSETTS.

BOBBIN AND SPINDLE CONNECTOR.

SPECIFICATION forming part of Letters Patent No. 760,704, dated May 24, 1904.

Application filed November 14, 1903; Serial No. 181,115. (No model.)

To all whom it may concern:

Be it known that I, FREDERICK W. SAWORSKI, of Boston, county of Suffolk, State of Massachusetts, have invented an Improvement 5 in Bobbin and Spindle Connectors, of which the following description, in connection with the accompanying drawings, is a specification, like characters on the drawings representing like parts.

10 This invention relates to a means for connecting a bobbin to a spindle, and more especially to that class of devices which connect the bobbin and spindle by means of spring-pressed fingers which engage the outer side 15 of the base of the bobbin.

The object of my invention is to produce a form of spindle and bobbin connector of the above-described character which is simple in construction, which may be made wholly of 20 parts which may be stamped out of metal, and which is provided with means which enable the bobbin-engaging fingers to maintain the same relative position with respect to the side of the base of a bobbin when in different positions with respect to the spindle. I accomplish this object by the means disclosed in the 25 accompanying drawings, in which—

Figure 1 is a side elevation of a spindle and bobbin provided with my improved connecting means. Fig. 2 is a plan view of the connector. Fig. 3 is a sectional view on the line $x-x$ of Fig. 2. Figs. 4 and 5 are sectional views on the lines $y-y$ and $z-z$, respectively, of Fig. 3. Fig. 6 is a side elevation of the 35 connector. Figs. 7, 8, 9, and 10 are detail views of one of the spring-fingers.

A bobbin a is mounted on the usual spindle b , said bobbin being of common form and having an enlarged base a' , provided with the 40 usual annular groove a'' .

The connector comprises two dished circular plates c d , oppositely arranged, with their bottoms clamped firmly together by a hollow rivet e , the latter being adapted to be driven 45 onto the spindle, so that it will be firmly secured thereon in the desired position. These plates thus unite to form a circular support having an annular groove f in its periphery. The upper plate c is provided with two rec- 50 tangular-shaped diametrically oppositely ar-

ranged notches $c' c''$, and two fingers g h are provided, one being arranged in each notch. Said fingers are each respectively provided with a semicircular-shaped spring $g' h'$, which are preferably formed integrally with their 55 respective fingers and extend at right angles therefrom. The sides of each finger g h fit somewhat closely into the notches $c' c''$ and are held against the bottoms thereof by the springs $g' h'$, which are arranged in opposite 60 portions of the annular groove f of the support, the end of one spring bearing against the outer side of the finger to which the opposite spring is connected, as shown in Figs. 3 to 6. As the bottom portion of each finger 65 forms one end portion of the corresponding semicircular spring of which the finger is a part and as the opposite end portion of the spring overlaps the other finger, it will be apparent that each spring is somewhat more than a semi- 70 circumference in length, and therefore by its own tension holds itself in the annular groove f by gripping the support in the bottom of said groove at points which are on the same side of a diameter, while the main portion of 75 the spring is on the opposite side of the same diameter. Said springs are each provided at their ends with an upwardly-arranged projecting lug $g'' h''$, said lugs being arranged in notches $c' c''$, the width of said lugs preferably 80 being less than half the width of said notches and the end portions of each spring extending across one of the notches $c' c''$, so that the side of the lug g'' or h'' thereon next the end of the spring rests against the adjacent side of the 85 notch.

The exact shape of the fingers g h is not wholly essential, but they preferably are bent so that their bobbin-engaging faces are slightly curved and their upper ends are outwardly flared to prevent them from catching on the bottom of the bobbin when it is put in place. 90

When the bobbin-base is forced down between the fingers g h , the latter will be moved 95 bodily outward in their respective notches a distance corresponding to the diameter of the bobbin-base, at the same time maintaining the same relative position with relation to the side of the bobbin-base within certain limits. It 100

will be observed while each spring to an extent holds its corresponding finger from outward movement that each spring also holds the opposite finger from such movement with 5 approximately the same degree of force.

As each finger is moved outward the end portion of the opposite spring which rests against it will be drawn across it, as indicated at the dotted position in Fig. 6, practically 10 the limit of the outward movement of a finger being reached when the inner edge of the lug which rests against it is drawn against the side of the notch in which it is located, as shown in Fig. 6.

15 Both fingers *g* *h* and their springs are exactly the same in all respects, so that they are interchangeable and may be stamped out with the same die. As each plate *c* *d* may be died out of sheet metal and as the means for 20 connecting them is simple and inexpensive, it will be apparent that the cost of making and assembling the parts will be small.

Having thus described my invention, what I claim as new, and desire to secure by Letters 25 Patent, is—

1. A spindle and bobbin connector comprising a circular support secured to the spindle and having a peripheral groove, and a pair of notches in the upper side thereof leading into 30 said groove, a bobbin-engaging finger arranged in each notch and extending upward from said support, and a spring connected to each finger, each spring being arranged in said groove and extending a part of the distance about said support, substantially as described.

2. A spindle and bobbin connector comprising a circular support secured to the spindle and having a peripheral groove, a pair of bobbin-engaging fingers extending upward therefrom, a semicircular-shaped spring connected to each finger and extending at right angles thereto from the lower end thereof, said springs being located in opposite portions of 45 said groove, the extreme end of the spring of one finger bearing against the outer side of the opposite finger, substantially as described.

3. A spindle and bobbin connector comprising a circular support secured to the spindle and having a peripheral groove and a pair of notches in the upper side thereof leading into 50 said groove, a bobbin-engaging finger arranged in each notch and extending upward from said support, and a spring connected to each finger, each spring being arranged in said

groove and extending a part of the distance about said support, a lug on the extreme end portion of each spring, each lug being of less width than said notches, and the lug of one spring bearing against the outer side of the 60 finger of the other spring, substantially as described.

4. A spindle and bobbin connector comprising a circular support secured to the spindle and having a peripheral groove a pair of bobbin-engaging fingers extending upward therefrom at diametrically opposite points, a pair of semicircular-shaped springs oppositely arranged in said groove, each spring being connected at one end to one finger and bearing 70 against the outer side of the opposite finger, substantially as described.

5. A spindle and bobbin connector comprising a circular support secured to the spindle and having a peripheral groove, a pair of bobbin-engaging fingers extending upward therefrom, and a spring connected to each finger, each spring being arranged in said groove and extending more than half of the distance about 75 said support, substantially as described.

6. A spindle and bobbin connector comprising a circular support secured to the spindle and having a peripheral groove, a pair of bobbin-engaging fingers extending upward therefrom, a semicircular-shaped spring connected 85 to each finger and extending at right angles thereto from the lower end thereof, somewhat more than half the circumference of said support, said springs being located in opposite portions of said groove, substantially as described.

7. A spindle and bobbin connector comprising a circular support secured to the spindle and having a peripheral groove, and a pair of notches in the upper side thereof leading into 95 said groove, a bobbin-engaging finger arranged in each notch and extending upward from said support, and a spring connected to each finger at one end, each spring being arranged in said groove and having a projection 100 on its opposite end arranged in one of said notches, substantially as described.

In testimony whereof I have signed my name to this specification in the presence of two subscribing witnesses.

FREDERICK W. SAWORSKI.
